UNITED STATES PATENT OFFICE

SIDNEY E. MEYERS, OF BUFFALO, NEW YORK, ASSIGNOR TO NATIONAL ANILINE & CHEMICAL CO. INC., OF NEW YORK, N. Y., A CORPORATION OF NEW YORK

EXPANSION COMPENSATOR

Application filed January 19, 1926. Serial No. 82,333.

This invention relates to a construction for counter-acting stresses arising in a double-walled vessel or structure due to differences in expansion of the walls.

5 In relatively long jacketed vessels, such as rotary vacuum dryers heated by jacket steam, the temperatures of the inner and outer walls are apt to vary to such an extent that an appreciable difference in the lengths of the 10 two walls occurs. The tubular formation of the walls presents a rigid unyielding construction and the result is that the end connections between the walls give way and leakage occurs.

15 According to the present invention this difference in linear expansion between the outer and inner walls of a dryer shell is compensated by introducing a break preferably in the outer wall surface anywhere intermediate the end connections so that the spaced wall sections thus formed can move linearly toward or from each other. To seal the opening thus made flanges, either integral or separate, are provided to extend from the adjacent ends of the sections. These flanges can be connected directly to each other or a 25 calking ring or its equivalent can be interposed.

The invention is illustrated in the accompanying drawing in which

Fig. 1 is a vertical cross section of a portion of the double wall of a dryer showing one form of compensating means; and

Fig. 2 is a view showing a modified form 35 of compensator.

The cylindrical inner wall 1 and the outer wall 2 are secured or rigidly connected by welding or other suitable means to end rings 3 and 4. The outer wall 2 is formed of two 40 sections, 5 and 6 having flanges 7, 8 extending from their contiguous ends. These flanges are suitably secured to a calking ring 9 as by rivets 10 or equivalent elements.

An alternative construction is shown in 45 Fig. 2 in which separate flanged rings 11, 12 are riveted or otherwise secured to the sections 5 and 6. The flanges are riveted to each other or to a calking ring as in the preceding form. A heating or cooling agent 50 may be supplied to the space between the walls

in either form through an inlet 13 or equivalent arrangement.

With either of these constructions, the function of the compensator is believed manifest. As the outer wall 2 is usually protected with heat insulating material it becomes relatively very hot due to the steam flowing between the two jackets, while the inner wall is comparatively cool on account of wet material in contact with it. Consequently during the drying action the outer wall is heated to a higher temperature and it expands to a greater lineal length than the inner one. This expansion is taken up by the spaced sections of the outer wall approaching each other and a consequent slight bending at the flanges. When the wall sections cool and contract, the flange connection again supplies the necessary give. In this way strains at the end connections of the 70 shell are avoided.

While the above disclosure is primarily directed to a dryer construction, the invention is applicable to other structures having parallel-arranged walls connected at their 75 ends and subjected to differential changes of temperature.

I claim:

1. In a dryer shell structure, parallel-arranged walls subjected to differential changes in temperature, one of said walls consisting of a single section, and another of said walls comprising a plurality of spaced sections and an expansion joint associating the spaced sections permitting relative linear movement of 80 the sections, and connections at the ends of said first mentioned wall uniting said walls.

2. In a dryer shell structure, parallel-arranged walls subjected to differential changes in temperature, one of said walls consisting of a single section, and another of said walls comprising a plurality of spaced sections, flanges extending from contiguous ends of 90 said sections, rivets uniting the flanges, and connections at the ends of said first mentioned wall uniting said walls and forming an enclosure.

3. In a dryer shell structure, parallel-arranged walls subjected to differential changes in temperature, one of said walls consisting 100

of a single section, and another of said walls comprising a plurality of spaced sections, flanges extending from contiguous ends of said sections, a calking member between said flanges, means securing said flanges to said member, and connections at the ends of said first mentioned wall uniting said walls and forming an inclosure.

4. A dryer shell construction comprising an inner cylindrical wall, an outer concentric wall, and end rings connecting the ends of said walls, said outer wall comprising spaced sections, flanges extending from the contiguous ends of said sections, a calking ring to which said flanges are secured.

In testimony whereof, I affix my signature.

SIDNEY E. MEYERS.
